SIGNAL CASING

Fred Clasing, Ruthven, Iowa

Application August 4, 1928, Serial No. 297,540

1 Claim. (Cl. 177—329)

This invention relates to signal devices for motor vehicles and particularly to that type of signal which consists essentially of a fixed casing having a plurality of compartments, individual lights in the compartments, and translucent coverings for the casing provided with signal symbols through which the rays of light project.

The principal objects of my invention are to provide a signal casing of this general character so constructed that a signal will be given from both the forward and rear faces of the casing; the light supporting element as well as the other parts are easily removed so as to facilitate replacement of the lights or such other parts while at the same time all the parts are normally, rigidly held in place on the casing; various parts are reversible and interchangeable so that the device is easy and cheap to manufacture and assemble; the exterior contour of the casing is smooth so that the device is easy to keep clean; and the wiring to the lights, while very easy to manipulate when necessary, is normally concealed where said wiring emerges from the casing so that it is out of sight and not liable to become pulled off or damaged when cleaning or otherwise working on the car adjacent the signal device.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claim.

In the drawing similar characters of reference indicate corresponding parts in the several views:

Fig. 1 is a perspective elevation of my complete signal structure.

Fig. 2 is a similar view of the casing proper, the covering and signal symbol plates being removed.

Fig. 3 is a perspective view of the cover detached.

Fig. 4 is a vertical transverse section of the complete structure.

Referring now more particularly to the characters of reference on the drawing, the numeral 1 denotes the casing proper, a rectangular member of suitable size and open both to the front and back. The casing is supported from the bottom by a bracket 2 which is adapted to be secured to a fender of the vehicle and having a vertical passage 3 therethrough which communicates with the interior of the casing. The casing

is preferably made of sheet metal and its edges intermediate the corners both at front and rear are bent inwardly to form flanges 4 disposed in vertical planes; such flanges being all depressed an equal amount relative to the edges of the casing at the corners as shown in Fig. 2. The casing at all corners is therefore formed with longitudinally extending flanges or ledges 5 projecting beyond the flanges 4, and providing means for locating the plates hereafter described in place to prevent such plates from having vertical or transverse movement relative to the casing.

Two plates fit snugly but removably between each set of ledges and rest against the adjacent set of flanges 4. The innermost plate 6 is of thin opaque material and is provided with a plurality of vertically spaced openings 7 of fanciful shape to represent various signal symbols; such openings being backed by a translucent cover sheet 8 secured to the plate 6. The various openings are so shaped that the plates may be inverted and the plate itself is of a size which will enable it to be fitted either at the front or back of the casing. The outer plate 9 is of the same size as the plate 6, but is entirely separate therefrom and is preferably a plain sheet of transparent glass. The thickness of the two plates together is such that the outer surface of the glass is substantially in vertical alinement with the outer ends of the ledges 5.

To hold the plates against displacement away from the casing, a cover 10 is provided which is the same shape as the casing, but has no bottom so that it slips over the casing from the top. The size of the cover of course is such as to enable it to have a free but not loose fit on the casing. The front and back of the cover are mainly open except for flanges 11 all around and which are sufficiently narrow so that they do not cover any portion of the signal openings 7. The cover is of symmetrical form both at front and back as well as on the sides so that it may be turned either way and still fit properly on the casing. It will therefore be obvious that when the cover is in place it will not come off unless the casing itself is actually inverted, so that securing means between the cover and casing are unnecessary. However, if desired, a holding screw 12 for engagement with the casing may be mounted in one side of the cover preferably near the bottom thereof. By means of this arrangement it will be evident that not only is the cover itself held from being dislodged by the particular manner in which it fits on the casing, but the various removable

plates are also positively held from displacement relative to the casing as long as the cover is in place.

The interior of the casing is divided into three vertically spaced compartments by means of opaque partition elements 13, which are vertically spaced a certain distance at the middle and converge to a fixed junction with each other at their ends as shown in Fig. 2 so as to form a single unit. This unit at its ends is supported and guided by V-shaped rails 14 mounted in the sides of the casing centrally of the height thereof, the vertical flanges 4 at one end of the casing being cut away about the rails so as to enable the partition unit to be slid out of the casing from that end.

The partition unit has a plurality of light-bulb supporting sockets 15 mounted therein and arranged so that the different bulbs will illuminate the various casing compartments formed by the partition unit. The partition is orificed where necessary to allow the wiring 16 from the various sockets to pass to the bottom passage 3 in the bracket, through which passage all the wires project. The partition is disposed relative to the signal openings 7 so that each opening will communicate only with one compartment in the casing. The partition structure is prevented from removal by one of the plates 6 when the latter is in position, and its removal of course enables the lights to be easily inserted or removed whenever necessary.

By means of the above described arrangement it will be seen that a very compact and neat appearing signal structure is provided, in which no

partition can become separated unless it is actually desired to do so and without the use of connecting screws or other similar securing means which require the use of tools of one kind or another to manipulate. It will be also seen that it is a very simple matter to remove or interchange any part simply by slipping off the cover.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claim.

Having thus described my invention what I claim as new and useful and desire to secure by Letters Patent is:

In a vehicle direction signal, an open sided casing having a peripheral flange at its open side, a partition structure for the casing forming a plurality of compartments and having a dimension such as to cause it to fit closely between opposed parts of the wall of said casing, said flange being provided with recesses cut therethrough and forming spaced slots for receiving the end portions of said partition structure and in part supporting the same, closure means for the open side of said casing seated on said flange, and an apertured cover member fitting over such open side and holding the closure means in place.
